Rogers, Kennedy, Campbell.

UNITED STATES PATENT OFFICE.

GEORGE FLETCHER HURT, OF NEW YORK, N. Y., ASSIGNOR TO JOEL HURT, OF ATLANTA, GEORGIA.

FEEDING MECHANISM.

Application filed May 31, 1917. Serial No. 171,918.

To all whom it may concern:

Be it known that I, GEORGE F. HURT, a citizen of the United States, residing at New York, in the county of New York and 5 State of New York, have invented certain new and useful Improvements in Feeding Mechanism, of which the following is a specification, reference being had therein to the accompanying drawing.

10 This invention relates to feeding mechanism for handling loose material and delivering the same in controllable quantity, the invention being more particularly concerned with the feeding of such materials 15 as stone, coal and the like, to grinding or pulverizing mills, although the invention is not limited to such special application.

In the feeding of material to machines of the character mentioned, in order to 20 obtain the best results the feed mechanism should be so constructed and operated that the material will be fed with regularity in prescribed quantity without liability of choking; the mechanism should be readily 25 adjustable to vary the quantity delivered by it in a given time; readily accessible and light to drive; and in connection with systems for transporting or separating solids by air circulation, the feed mechanism 30 should be so constructed that there will be a minimum of air leakage.

My invention comprehends a feeding mechanism which combines in its structure these several desirable functions and characteristics, the mechanism in accordance with 35 my invention consisting of a traveling feeding member, preferably in the form of a rotary feeding wheel, mounted in a hopper and containing pockets or compartments 40 of prescribed size, which in course of the rotation of the wheel are one at a time filled with material from the hopper, and the material delivered by the wheel in successive increments, the said wheel cooperating with 45 a gate which is yieldable to prevent clogging, and which may also be adjustable to vary the quantity of material in the successive increments.

In the accompanying drawings:

50 Fig. 1 is a vertical sectional elevation through a feeding mechanism having my invention embodied therein.

Fig. 2 is a top plan view of the same.

In the accompanying drawings I have 55 shown my invention in a form and embodied

ment especially adapted for use in feeding the material into the side of the grinding chamber of a pulverizing mill, but it will be understood that the invention is not limited to such use, and that the construction shown may be modified to adapt the same for application with other types of machines without departing from the limit of my invention.

In the construction shown, 1 indicates a vertical hopper to receive the material to be fed, which hopper is connected at its lower end to a downwardly inclined throat 2, the lower end of which is adapted to be fastened around an opening in the side of the casing of the grinding mill so that the material entering the throat from the hopper will be directed into the mill. 3 designates a traveling feeding member in the form of a horizontal feeding wheel or drum which is provided with a series of compartments or pockets 4 open at the periphery of the wheel and of prescribed and equal size, the said pockets in the present case being formed by a series of longitudinal radial partitions 5 extending outwardly from the hub of the wheel, and disk-like members 6 at the opposite ends of the wheel, which disk-like members constitute the end walls of the pockets. This wheel is mounted in the upper end of the throat at the lower end of the hopper where it joins the throat, and is fixed to a horizontal shaft 7 mounted in suitable bearings on the side walls of the throat, which shaft has fixed to it outside the hopper, a pulley or other suitable driving device 8 by which rotary motion may be imparted to the wheel in the direction of the arrow in Fig. 1 from any suitable source of power. Mounted in the hopper is a chute plate 9 which extends from near the upper end of the same at a downward and forward slope or inclination, this plate constituting in effect the bottom of the hopper, and which plate, due to its forward and downward inclination will act to direct the material in the hopper into the pockets in the feeding wheel. At its lower end this chute plate is formed with an open recess 10 which corresponds approximately in size and shape to the size and shape of the open end of the pockets, the intact portions 9a of the chute plate at the sides of the recess overlying the end walls of the pockets, as shown more par-

105
110

ticularly in Fig. 2. The rear walls of the recess extends in close proximity to the path of movement of the outer edges of the walls of the pockets, and as the advancing partition of a pocket passes by the wall of the recess, the pocket will be gradually uncovered so that the material will flow thereinto from the chute plate 9, and as the motion continues, the pocket will be fully 10 uncovered as shown in Fig. 1, and brought in full registry with the recess in the chute plate. It is seen, therefore, that in the rotation of the wheel, the pockets will be filled in succession by the material in the 15 hopper, and the contents of the same will be delivered to the throat in successive increments.

The wheel in its rotation cooperates with a cut-off device or gate 11 in the form of a 20 vertical plate which is mounted to slide freely in a vertical guide in the front wall of the hopper, the lower edge of the vertical gate extending in close proximity to the periphery of the wheel. At its upper end 25 the vertical gate is provided with a lateral stop lug 12 which engages the upper end of the hopper wall, or an adjusting device, and determines the closest operative relative position of the lower edge of the vertical 30 gate to the periphery of the feeding wheel. As the feeding wheel rotates, this vertical gate serves to control the amount of material entering the throat below the pockets, and when adjusted with its lower edge 35 in close proximity to the periphery of the wheel, as shown in Fig. 1, it will act to cut off any surplus material tending to enter the discharge throat, thereby causing each pocket to receive and deliver to the throat 40 with uniformity the prescribed quantity of material. When, however, the vertical gate is adjusted with its lower edge a greater distance from the periphery of the wheel, which adjustment may be effected by inserting beneath the lug 12 a liner 13, or by 45 other suitable means, the pockets will be permitted to discharge the quantity of material they actually hold and also an additional quantity which is superimposed above 50 the pockets and is carried along by the friction of the material and by gravity, and therefore a greater amount will be delivered by the wheel to the throat. In this manner and by adjusting the vertical gate to different 55 positions relative to the wheel, the amount of material delivered by the wheel under a given speed of rotation, may be accurately and effectively controlled.

By mounting the vertical gate so that it 60 is freely movable in its guide, it will act by gravity to maintain its proper operative position relative to the feeding wheel, and yet will readily raise to permit the passage of obstructions formed of one or more 65 pieces which might be carried in the pockets

and which projecting outwardly therefrom, would otherwise interfere with the rotation of the wheel and clog the parts. In the rotation of the wheel, such obstructions will be carried against the lower edge of the vertical 70 gate and the latter will be lifted as the motion of the wheel continues, and the obstruction will be permitted to pass thereunder without interference with the rotation and the consequent clogging of the wheel. The 75 lifting action on the gate by the obstruction under the condition mentioned, is facilitated by the fact that the lower end of the gate is disposed forwardly of the axis of rotation of the wheel so that the obstruction will be 80 carried by the wheel in a downward path angularly related to the vertical yielding movement of the gate, the tendency of the obstruction being thus to lift the gate rather than to bind the same in its guides, 85 which would occur if the obstruction were carried against the gate at right angles to its lifting movement.

As a result of the mechanism described, the material will be delivered by the wheel 90 from the hopper in uniform prescribed quantity and in regularly recurring successive increments without liability of clogging, and by the adjustment of the gravitating vertical gate the quantity delivered may 95 be varied without changing the speed of rotation of the wheel, or the size of its pockets, in order to meet the varying conditions encountered in operation with respect to the capacity of the mill, such as the character 100 of the material being handled and other conditions.

The intact portions of the chute plate or shield 9, at the sides of the recess therein, by extending above and overlying the ends of 105 the wheel will effectually prevent the fine particles of material from working around beyond the ends of the wheel; and due to the fact that the opening in the bottom of the hopper, through which the material enters the pockets, is closed at its four sides by the walls of the recess in the plate 9 and the lower end of the cut-off plate, the leakage of air into the throat and thence into the grinding chamber of the mill, is reduced to 110 a minimum, this feature of the invention being of particular advantage when the feeding mechanism is employed in connection with the systems for transporting or separating materials by air suction or pressure. 115

In the accompanying drawings and foregoing description I have disclosed my invention in the particular form and detailed construction which I prefer to adopt, but it will be understood that various changes 120 may be made in these details, and that the construction may be variously modified without departing from the limits of my invention provided the operation is substantially as above set forth; and it will be fur- 125 130

ther understood that the invention is not limited to any particular form or construction of the parts except in so far as such limitations are specified in the claims.

5 Having thus described my invention, what I claim is:

1. In combination with a hopper having a rectangular discharge opening in its bottom open at its forward side, a feed wheel 10 rotatably mounted below said opening and provided with open pockets closed at their ends by end discs on the wheel, the inner faces of which align with the sides of the discharge opening, and an upright gate 15 guided vertically in the front of the hopper and having its lower end arranged to close across the open front of the discharge opening in proximity to the periphery of the feeding wheel, said gate being freely movable bodily in a vertical direction to permit 20 obstructions to pass.

2. In a feeding mechanism the combination 25 of a hopper comprising opposing upright side walls, an upright front wall, and a forwardly and downwardly inclined rear wall

extending between the side walls and provided at its lower end at the sides thereof with two forwardly extending substantially horizontal extensions terminating adjacent the lower end of the front wall, whereby a 30 discharge opening is formed in the bottom of the hopper between said extensions and the lower ends of the front and rear walls, a feeding wheel provided with open pockets and end discs closing the ends of the pockets, 35 said wheel being rotatably mounted beneath the discharge opening with its end discs extending at the under sides of the said extensions, and an upright gate guided vertically in the front wall and having its lower end 40 extending below said wall and in proximity to the periphery of the wheel, said gate being freely movable bodily in a vertical direction, whereby the gate will determine the amount of material delivered by the respective pockets, and will yield to permit the 45 passage of obstructions.

In testimony whereof, I have affixed my signature.

GEORGE FLETCHER HURT.
